Primary Examiner — Brett Miller*Assistant Examiner* — Sara Michie Pottenger(74) *Attorney, Agent, or Firm* — SMART & BIGGAR
LP; Tonino Rosario Orsi(57) **CLAIM**

The ornamental design for a lift structure as shown and described.

DESCRIPTION

FIG. 1 is a front perspective view of a lift structure including a control podium in accordance with a first embodiment; FIG. 2 is a further front perspective view of FIG. 1; FIG. 3 is a front view of FIG. 1; FIG. 4 is a rear view of FIG. 1; FIG. 5 is a side view of FIG. 1; FIG. 6 is further side view of FIG. 1;

FIG. 7 is a perspective view of a lift structure of FIG. 1 without the control podium in accordance with a variant of the first embodiment; FIG. 8 is a front view of FIG. 7; and, FIG. 9 is a side view of FIG. 7, the opposite view being a mirror image thereof.

The design is the visual features of a lift structure shown in solid lines in the drawings.
